PRINTING PLATE LOCK-UP

Henry A. Wise Wood, New York, N. Y., assignor
to Wood Newspaper Machinery Corporation,
New York, N. Y., a corporation of Virginia

Application May 20, 1930, Serial No. 453,964
Renewed July 9, 1932

10 Claims. (Cl. 101—378)

The principal object of this invention is to provide a cylinder operated plate lock-up means usually operable by the turning of the cylinder but by which also the plate can be locked or unlocked manually and also to provide a simple construction which may be applied to existing presses.

Other objects and advantages of the invention will appear hereinafter.

Reference is to be had to the accompanying drawings in which

Fig. 1 is a plan of a printing press cylinder with the plates removed, showing a preferred embodiment of this invention;

Fig. 2 is an end view of the same;

Fig. 3 is a sectional view on the line 3—3 of Fig. 1 showing the means for operating the end plate clamp and showing the plate in position;

Fig. 4 is an end view of the cylinder showing the manual means for unlocking the plate, and

Fig. 5 is a plan of the same.

The printing cylinder 10 is provided with longitudinal slots in certain of which are rigid blocks 11 near each end of the cylinder. This block preferably is either integral with the cylinder or fixed immovably in position. Through this block extends a spring rod 12. A spring 13 on the rod bears against the block and against a collar 14 fixed to the rod as an abutment. Therefore this rod which passes through the end clamp 15 into an end block 16 to which it is adjustably but firmly secured will normally tend to pull the end clamp 15 against the printing plate P. The rod 12 has a shoulder at the inner side of the clamp. The center clip 16 is movable and the rod 12 passes through it and has a collar 17 adjustably mounted on the inner end.

In the end block 16 is a pivot pin 20 which is connected by a link 21 to a segment arm 22 pivoted on a stud 23. This arm has a segment 24 on the opposite end. This segment meshes with teeth on one side of a segmental gear 25 fixed on a stud 26. The other side of this gear meshes with an intermediate gear 27 on a stud 28 having a polygonal end 29 for receiving a wrench. The intermediate gear meshes with a segment 24 on a second segment arm 22 exactly like the first named segment arm and connected with a link 21 for operation by a second spring rod to force the second end clamp 15 against a plate.

The studs of the segment arms and gears are mounted with one end in the cylinder itself and the other end has a bearing in a bearing bracket 30 which is attached to the cylinder. On the stud 26 is fixed an arm 31 having a roll 32 carried by a stud thereon. The cylinder and bearing bracket

also carry a stud 33 which has a polygonal end 34 for receiving a wrench and also carries a latch 35 adapted to hold the segmental gear 25 by coming into contact with a radial surface thereon but normally movable on a concentric surface 36 on this segmental gear 25. A spring 37 forces this latch against the gear and into the position shown in Fig. 1 whenever the gear moves that far.

In Figs. 4 and 5 is shown a hand-operated means for actuating the roller 32 to unlock the plate. This consists of a stud 40 mounted on the frame of the machine and carrying a lever 41. One end of this lever is operated by a spring 42 to normally force the lever back from the position shown in Fig. 4. When it is to be operated the attendant presses down the handle 43 and moves it into the position shown in Fig. 4. In this position as shown in Fig. 5 a cam 45 on the lever 41 is located in position for the roll to engage it when the cylinder comes around to the proper position. The object of this is to move the roll as shown by the arrow in Fig. 1 to unlock the plates, the latch 35 resting at that time on the surface 36. When the roll is moved in that direction it, of course, turns the gears in such a direction as to pull out the two spring rods, thereby releasing the two end clamps. When it is desired to operate the press without the plate at the end of the cylinder and only the center plate in place, the spring 13 presses the collar 14 against the center clip 16 thereby placing the pressure directly on the center clip so that the next plate will be held firmly in position. In the unlocking of the plates the collar 17 engages the center clip and pulls it away from the next plate.

Operation

It will be understood that when putting the plates on the cylinder or taking them off a man has to be stationed at each side of the cylinder for the purpose of putting the plates in position or taking them off. There is one of these operating devices at each side and the same man can handle it. The operator presses the jog button with one hand while grasping the handle 43 in the other so that the cylinder will rotate slowly. He pulls the handle down so that the cam engages the roll when the cylinder, rotating slowly, comes around to bring the roll into proper position. The cam is so shaped that once the roll engages the angularity of the cam that is sufficient to prevent its rising until the roll has rolled off the cam.

In some cases it may be desirable to operate this mechanism for locking up the plate manually without rotating the cylinder to do it, especially

in case of emergency. For that purpose a hexagon end 29 is provided for the reception of a wrench. Here the intermediate gear 27 is turned slightly further than when operated in the usual manner so that the pawl 35 will come down to the position shown. When it is desired to re-lock the plates after manual operation it is only necessary to place the wrench on the hexagonal end 34 and rotate it enough to disengage the latch. 10 The force of the springs 13 will then move the end clamps against the plate and turn the locking parts to their normally locked position.

It will be understood of course that ordinarily the plates are locked simply by the rotation of 15 the cylinder as has been the case heretofore. This invention is unique in that the plates can be locked manually without rotating the cylinder, as well as being unlocked manually.

It will be seen that the construction is comparatively simple and that the locking can be manipulated manually in either direction with or without a plate on the cylinder. Each end of 20 the plate is held on by two clamps. In other words there are four clamps to a set of plates and two separate operating mechanisms on each 25 end of each plate cylinder. All these parts are carried by and rotate with the plate cylinder and are located beneath its surface.

Although I have illustrated and described only 30 one form of the invention I am aware of the fact that modifications can be made therein by any person skilled in the art without departing from the scope of the invention as expressed in the 35 claims. Therefore I do not wish to be limited in this respect but what I do claim is:—

1. In a printing plate locking device, the combination with a cylinder on which the plates are mounted, an end clamp for the plate and yielding means for forcing the end clamp against the plate, of mechanism carried by the cylinder for moving the end clamp away from the plate in opposition to 40 said yielding means, a cam adapted to be located in position to be engaged by said mechanism as the cylinder rotates to operate the mechanism to withdraw the end clamp, and means for manually actuating said mechanism when said cylinder is at rest to move the end clamp toward or from the plate.

2. In a printing plate locking device; the combination with a cylinder on which the plates are mounted, end clamps for the plate and yielding means for forcing the end clamps against the plate to be locked, of a segmental gear, an intermediate gear meshing with the segmental gear, said intermediate gear having its end shaped to receive a wrench for hand operation, means operated by the gears for moving the end clamps away from the plates in opposition to said yielding means, an oscillatable member carried by the 45 gearing and a cam located in position to be engaged by said member as the cylinder rotates to withdraw the end clamps, when the cylinder is at rest.

3. In a printing plate locking device, the combination with a cylinder on which the plates are mounted, end clamps for the plates and yielding means for forcing the end clamps against the plate to be locked, of mechanism carried by the cylinder for moving the end clamps away from the plates in opposition to said yielding means, a cam adapted to be located in position to be engaged by said mechanism as the cylinder rotates to operate the mechanism to withdraw the end clamps, means for manually actuating said mechanism when the cylinder is at rest to move

the end clamp toward or from the plate, said mechanism comprising a segmental gear cooperating with the rest of the mechanism to turn therewith or to be turned thereby and having a stop thereon, and a latch in position to engage 80 said stop when the segmental gear is turned by hand to withdraw the end clamp, said latch having connected therewith an end shaped to receive a wrench, whereby the latch can be withdrawn by hand after the clamps have been operated by hand to restore them to position to be operated by the rotation of the cylinder. 85

4. In a plate lock-up, the combination with a cylinder and two end clamps for a plate thereon, of spring rods connected with said end clamps for holding them in position for locking the plate, links connected with both arms, segmental arms connected with said links, each having a gear segment thereon, a segmental gear having two gear segments, one meshing with said arm, an intermediate gear meshing with the other gear segment and the other segmental arm, and an arm oscillatable with the gear segment and having a roll thereon. 90

5. In a plate lock-up, the combination of a 100 movable end clamp, a rod extending through the end clamp, a spring connected with the rod for normally moving the rod in to clamp a plate on the cylinder, a link connected with the rod, a segment arm pivotally connected with the link and 105 having a gear segment thereon, a gear segment meshing therewith, an arm movable with the said gear segment and a roll on the last named arm for operating the gearing to release the end clamp. 110

6. In a plate lock-up, the combination with a movable end clamp and a spring for moving it into position automatically to lock the plate, of a rod connected with the spring, an oscillatable arm mounted on the cylinder and provided with a roller and connected with the rod for operating it, and a hand lever provided with a cam adapted to be moved by the lever into position for engagement with the roller when the cylinder rotates past it for forcing the roller in 120 a direction to move the rod out to release the end clamp. 115

7. In a plate lock-up, the combination with a cylinder and an end clamp for a plate thereon, of a spring rod connected with said end 125 clamp for holding it in position for locking the plate, a link connected with said arm, a segmental arm connected with said link, having a gear segment thereon, a segmental gear meshing with said arm, an arm oscillatable with the 130 gear segment and having a roll thereon, a hand operated lever pivoted on a stationary part of the machine and provided with a cam adapted to be moved into a position to engage said roll and cause it to move to a position for unlocking 135 the end clamp, and means for normally holding said cam out of the path of said roll.

8. In a plate lock-up, the combination with a movable end clamp and a spring for moving it into position automatically to lock the plate, a 140 rod connected with the spring and passing through to the end of the cylinder, an oscillatable arm provided with a roll and connected with the rod for operating it, the arm being mounted on the cylinder, a hand lever provided 145 with a cam adapted to be moved by the lever into position for engagement with the roll when the cylinder rotates past it for forcing the roll in a direction to move the rod out to release the end clamp, a stud on which said arm is fixed, a 150

stop on the stud, a spring pressed latch adapted to engage the stop when the arm is moved to a complete unlocking position and hold it there and means whereby the latch can be turned back by 5 hand to release the arm.

9. In a plate lock-up, the combination with a cylinder and an end clamp for a plate thereon, of an operating roll connected with the end 10 clamp for unlocking it, a hand operated lever pivoted on a stationary part of the machine and provided with a cam adapted to be moved into a position to engage said roll and cause it to

move to a position for unlocking the end clamp, and means for normally holding said cam out of the path of said roll.

10. In a printing plate locking device, the combination of a printing cylinder, yielding means for holding a plate on the cylinder, and means controlled by the rotation of the cylinder to operate said locking means to unlock the plate against the resistance of said yielding means, of means for manually operating said yielding means. 85
